1

This invention relates to machines for grinding the tooth flanks of gear wheels.

It is already known to grind the tooth flanks of externally toothed gear wheels by an involute generating process involving the use of two grinding wheels, one for each side of a tooth or of two teeth.

Such machine, however, are not generally suitable for grinding the tooth flanks of internally toothed gear wheels, because the space within the annulus of such a gear is too restricted to accommodate two grinding wheels and to allow for the necessary movements thereof. Moreover, as the tooth flanks of internally toothed gears with teeth of involute form are concave it is not possible to use a grinding wheel of which the working part is a plane surface, as is the case in known machines for grinding externally toothed gears. In its place a grinding wheel is employed having an operative rim which makes substantially point-contact with the tooth flank.

The object of this invention is to provide an improved machine by which the grinding of internally toothed gear wheels, including those with inclined or helical teeth, can be efficaciously carried out and which, at the same time, retains most of the advantages of the known gear grinding machines above referred to.

According to the present invention, a single grinding wheel is provided for grinding the tooth flanks of internally toothed gears by an involute generating process, such grinding wheel being mounted for pivotal movement about an axis which is perpendicular to, but does not intersect, the grinding wheel axis in such a way that, by pivoting the grinding wheel through approximately 180°, it can be brought into position for grinding the other side of the teeth as well.

For grinding the flanks of closely pitched internal teeth, the gaps between which are accordingly small, it is necessary for the rim of the grinding wheel to be correspondingly narrow. In order to strengthen the grinding wheel it is usually made dished or saucer-shaped. This means, of course that the grinding wheel always operates with the same edge or rim, but by making it carry out a pivotal movement in accordance with this invention, the working edge or rim can be made to face either way and hence to grind both sides of the teeth.

According to a further feature of the invention, the relation between the grinding wheel axis and the axis about which it is adapted to pivot may be such that, after pivoting through about 180° the working point of the grinding wheel, which

2

in operation lies on the base circle of the gear wheel, is initially situated too high for proper operation, namely well above the base circle, and the grinding wheel is mounted for free vertical sliding movement between adjustable stops relatively to the axis about which it pivots so that immediately after the pivotal movement, it drops by gravity back to the correct position, determined by the stops, with its working point on the base circle of the gear being ground.

This arrangement makes it possible, by adjustment of the stops, to allow for the use on the same machine of grinding wheels of different diameters and for reduction in diameter by wear or by a cutting device such as is usually provided for this purpose in order to renew the operative edge or rim of the grinding wheel.

A lateral or horizontal adjustment of the grinding wheel may also be provided for in order to compensate for wear of the operative rim at the side thereof and for the action of a lateral dressing device which is usually incorporated. For this purpose, the machine incorporates a feeler device of a kind known per se, which is kept in engagement with the side of the rim and which automatically brings about the said lateral adjustment of the grinding wheel as the thickness thereof at the rim is reduced either by wear or after the dressing device has been in use between grinding operations. This lateral adjustment is preferably obtained by mounting the grinding wheel on a tool-holder which in turn is carried by a slide in a manner permitting horizontal adjustment of the tool-holder with respect thereto under the automatic action of the feeler device, the slide being mounted, for vertical movement between the aforementioned stops, on a turn-table rotatable about the aforementioned pivotal axis.

It will be seen that, if the stops are adjusted when a reduction in diameter of the grinding wheel has occurred the device for turning the grinding wheel down to reduced diameter and the feeler device will require to be advanced towards the centre of the grinding wheel. According to a further feature of this invention, provision may be made whereby both these devices are adjustably mounted and their means of adjustment are coupled with the means for adjusting the stops in such a manner that, when the stops are adjusted, the two devices are automatically advanced by a like amount.

Preferably, the machine is so arranged that the grinding wheel makes no movement in space while a grinding operation is in progress (i. e.

apart from the adjustments mentioned in the foregoing), its working point remaining stationary upon the base circle of the gear being ground, whereas the latter is fed forward towards the grinding wheel whilst at the same time executing an oscillatory true rolling motion which is necessary for grinding the teeth to involute form and which is constituted by a combined rotary and lateral reciprocating motion.

In order to enable the invention to be readily carried into effect, one embodiment thereof will now be described by way of example with reference to the accompanying drawings. This description will also make apparent other features of the invention and the application thereto of the advantageous features of known machines, including those which enable both straight and inclined or helical teeth to be ground by an involute generating process.

In the accompanying drawings:

Figs. 1 and 1a, viewed together, constitute a side elevation of a form of gear grinder embodying the invention, certain parts being shown in vertical longitudinal section;

Figs. 2 and 2a, viewed together, constitute a top plan of this form of gear grinding machine showing certain parts thereof, particularly of the grinding wheel mounting and adjusting apparatus, in horizontal section;

Fig. 3 is an end view of the top part of the machine viewed from the left of Figs. 1, 1a, 2 and 2a showing the apparatus for imparting the rolling motion to the work;

Fig. 4 is an elevation in vertical transverse section of the grinding wheel mounting and adjusting apparatus only, the section being taken approximately on the line IV-IV of Fig. 1a, though certain parts on the left of the section line of Fig. 1a are also indicated in Fig. 4 for a better understanding;

Fig. 5 is an end elevation of the grinding wheel mounting and adjusting apparatus only, viewed from the right of Figs. 1a and 2a, the parts designated by reference numerals 2, 3 and 4 in Figs. 1a and 2a (as well as parts associated therewith) being omitted in Fig. 5.

The form of machine shown in the drawings comprises a bed 1 (Figs. 1-3) on which is displaceable in the direction of the longitudinal axis B of the machine a lower slide 48 having an upper slide 47 mounted thereon displaceable transversely of the axis B. The upper slide 47 carries a rotatable work-holder 45 which is adapted to have fixed thereon the internally toothed gear 30 to be ground. Also mounted for rotation on the slide 47 is a shaft 46 which is co-axial with the tool-holder 45 and is connected thereto through the intermediary of a dividing or indexing device which, being of known construction and function, has not been indicated in the drawings, nor is any description thereof thought necessary. Mounted on the shaft 46 is a rolling arc 49 (in the form of a cylinder or part of a cylinder shell or, as shown, a segment of a cylinder) of a diameter corresponding to the base circle diameter of the gear being ground. Connected to the circumference of this rolling arc 49, at opposite sides thereof, are flexible steel tapes 50, the other ends of which are fastened to levers 51 pivoted to a frame 52 mounted on the lower slide 48. The slide 48 is driven to make a feed movement towards the grinding tool 13 (to which detailed reference will be made hereinafter), and it is adapted, through a crank drive 54 mounted on the slide 48, to reciprocate the upper slide 47 perpendicularly to

its own movement. The steel tapes 50, being held by the frame 52 which does not take part in this reciprocating movement, roll on and off the rolling arc 49 and cause the latter to rotate as it traverses across the machine with the upper slide, thereby imparting to the gear 30 being ground a true rolling motion relatively to the grinding tool 13 so that the latter, when in contact with a tooth of the gear 30, grinds the tooth flank to involute form. The grinding wheel 13 does not move in space during this operation, and its point of contact with the tooth flank is and remains in a plane passing through the steel tapes 50. The latter, being tangential to the rolling arc 49 and, hence, to the base circle of the gear being ground, represent in concrete form the line known as "line of action" of the gear being ground. The drive ratios are so chosen that, during a slow feed motion of the lower slide 48, many traversing motions of the upper slide 47 take place. The dividing or indexing device previously referred to periodically causes the gear 30 to be rotated (without rolling) so as to bring another tooth flank up against the tool 13.

In many cases, it is of advantage so to grind the tooth flanks that their portions near the tip and/or root of each tooth are rounded off, i. e. deviate slightly from the true involute form at these places, because this gives better performance in the use of two mating gears which are under a particularly heavy load. This is dealt with in co-pending U. S. application Serial No. 69,273 filed January 5, 1949 and issued as Patent No. 2,486,020 on October 25, 1949 which discloses means for bringing about such localised deviations from the involute tooth form. Similar means are also incorporated in the present embodiment, and a detailed description thereof is considered unnecessary. It will suffice to point out with reference to Fig. 3 that the tape-holding levers 51 have tape-tensioning screws 56 mounted therein which bear on movable elements 57 mounted in the frame 52. In response to actuation by the means above referred to and not described herein, the elements 57 jointly make a small movement to the left or to the right as viewed in Fig. 3, at the very moment when the tool 13 is grinding a tip or a root portion of a tooth flank, thereby pivoting the levers 51 in unison and imparting, through the tapes 50, a small rotary motion to the rolling arc 49 additional to its rotary motion obtained by its reciprocation relatively to the tapes, such additional rotary motion being of course transmitted to the work 30 at those moments and causing the tool to take off a little extra material at those places and thereby to produce the desired rounding off, whilst at other times the levers 51 do not move relatively to the frame 52 so that the remainder of the tooth flank is ground to true involute shape.

The grinding wheel and its manner of mounting, operation and adjustment will now be described.

Referring first to Figs. 1, 1a, 2 and 2a, the machine bed 1 has mounted thereon a frame structure in the form of a standard 2 which can be turned about a vertical axis C with respect to the bed 1 by means of a pivot pin 55. A slide 3 is carried by the standard 2 and is vertically displaceable thereon by means of a screw spindle 4 operated by a hand wheel. A second slide 5 is mounted on the slide 3 for horizontal adjustment with respect thereto, preferably by hydraulic or pneumatic means to be described hereinafter. The slide 5 carries a turn-table 6 which is rotat-

able thereon about an axis A (Figs. 4 and 5) by means of a pin 7 on the turn-table 6 journalled in a bearing in the slide 5. Rotation of the turn-table is effected manually or automatically by means of a worm gearing 8, the worm wheel being formed on a circular flange of the turn-table (Fig. 1a). Mounted on the latter is a further slide 10 which is vertically movable with respect to the turn-table 6, being guided in linear ball-bearings 11 provided therebetween (Figs. 2a and 5). The slide 10 carries a tool holder 12 which is horizontally adjustable with respect thereto. The tool holder 12 supports, and provides the bearing for rotation of, the grinding wheel 13, and in addition it supports a motor 14 for driving the grinding wheel 13 by means of a belt 15.

Horizontal adjustment of the tool holder 12 along the slide 10 is automatic for the purpose of ensuring that the tool is at all times during the grinding operation maintained in proper working position with respect to the work. Thus, if the working rim of the grinding wheel 13 should become worn down, the tool holder is automatically moved closer to the work by a corresponding distance. Devices for effecting such adjustment are already known, for example from U. S. Patent No. 1,228,798 which may be referred to for further details. For the purpose of an understanding of this embodiment of the present invention, it will be sufficient to point out that a feeler 16 mounted on the slide 10 is provided which is kept in constant engagement with the working rim of the grinding wheel and if, for example, the rim becomes worn the feeler 16 transmits its movement through two pairs of bevel gears 24 and 25 respectively, to an eccentric 26 which operates a pawl 17 (see Figs. 1a and 4) to rotate a ratchet wheel 18 through an angle corresponding to one tooth thereof per revolution of the eccentric 26. The rotation of the ratchet wheel 18 is transmitted, via gearing 19, 20, to a screwed spindle 21 (Fig. 2a) which is engaged by a nut secured to the tool-holder 12 and thereby effects the horizontal movement thereof relatively to the slide 10 against the action of a spring 22 which prevents overrunning of the device by ensuring that the horizontal adjustment of the tool-holder stops as soon as the impulse given by the feeler 16 ceases. The tool-holder 12 is guided in its horizontal movement by linear ball-bearings 23 (Figs. 1a and 4).

There is only one grinding wheel 13, and it is dished or saucer-shaped. It works within, and with its upper rim in contact with a tooth flank near the top of, the annulus of the internal gear being ground (such as 30). The rim only makes point-contact with the tooth flank, or to be more precise, only a very small area of the rim contacts the tooth flank.

As the internal gear 30, while being slowly fed forward towards the grinding wheel 13 by the feed slide 48, is oscillated back and forth with a true rolling motion by the traversing slide 47 in co-operation with the tapes 50, the grinding wheel 13 grinds one flank of one tooth to the correct involute shape subject to possible deviation from this shape at the tip or root of the tooth, as described. During this operation the point of contact P (Fig. 3) of the grinding wheel rim (i. e. where the latter contacts the tooth flank) never moves in space; the wear compensating device 16-26 above described keeps it in the same place, namely on the base circle tangent or "line of action" (plane of 50, see Fig. 3), a little to one side of the longitudinal central plane B of the ma-

chine (see Fig. 2). When the other flank of the tooth (or of another tooth) is to be ground, the turntable 6 is rotated through about 180° about the axis A, thereby inverting the tool holder 12 and pivoting the grinding wheel 13 through the same angle. For this purpose the worm gear 8 is operated and the rotary movement is limited by engagement of an adjustable screw stop 27 with one of two abutments 28 provided on the slide 5 (Figs. 2a and 5). In the present embodiment the axis A is contained in the plane of the working rim of the grinding wheel 13 (Fig. 4). It is perpendicular to, but does not intersect the grinding wheel axis which, in the operating position of the grinding wheel, is located below the axis A. Upon inversion of the grinding wheel, as just described, although the latter then presents its operative rim to the opposite tooth flanks, its point of contact P would, owing to the described relation between the grinding wheel axis and the axis A, be well above the base circle if it were not for the vertical sliding movement of the holder 12 jointly with the slide 10 relatively to the turn-table 6. As the slide 10 is inverted by rotation of the turn-table 6, so it drops by gravity relatively to the latter along the ball bearing guides 11. For this purpose, slide 10 is freely movable with respect to the turn-table 6, but is associated with two adjustable stops 29, one of which normally rests on an abutment provided by one edge of a projection or boss 31 on the turn-table 6 to limit the downward movement of the slide 10. The stops 29 are in the form of nuts engaged on oppositely threaded portions of a spindle 32 by rotation of which both stops can be simultaneously adjusted to occupy positions thereon appropriate to the positioning of the slide 10, and hence of the grinding wheel, so that the point of contact P of the latter comes to lie on the base circle of the gear being ground. The spindle 32 is mounted in the slide 10 for rotation but secured against axial movement with respect thereto. Upon rotation of the turn-table 6 with the slide 10 to invert the latter, the other stop 29, previously lowermost, comes uppermost, and the slide 10 drops vertically until this other stop 29 rests on its associated abutment constituted by the other edge of the boss 31. In this way, the point of contact P of the grinding wheel 13 which had momentarily been situated too high in relation to the work being ground, is brought down again to its previous position on the "line of action" or tangent of the base circle of the gear being ground. In both positions the general plane of the grinding wheel forms the same angle with the vertical plane. In practice, it is usual to grind first all the tooth flanks facing in one direction, then to invert the grinding wheel in the manner just described and to grind all the tooth flanks facing in the opposite direction, no manual adjustment being normally necessary during these two grinding operations, as the indexing device above referred to automatically turns the work to present the next tooth to the grinding wheel when the grinding of one tooth is finished. The inversion of the grinding wheel is repeated when it is desired to grind again the tooth flanks facing in the first direction, the other stop 29 then resuming cooperation with its abutment on the boss 31.

After inversion, the grinding wheel rim must be moved laterally into contact with a tooth flank, and this is done by the horizontal adjustment of the slide 5 with respect to the slide 3. This adjustment is of course also made, when the ma-

chine is first set for grinding a particular internal gear wheel, in order to predetermine the thickness of material to be removed from the tooth flanks during such operation. For the purpose of effecting this lateral adjustment, the slide 3 has a spindle mounted therein for rotation and axial reciprocation with respect thereto. This spindle comprises oppositely screw-threaded portions 36 and 37 (by which numerals the spindle itself will hereinafter be identified), which are engaged by nuts 38 and 39 mounted thereon for axial movement but secured against rotation. The nuts 38 and 39 are adapted to act as stops limiting the axial movement of the spindle 36, 37 by engagement with abutments provided by 15 projections on the slide 3, as shown in Fig. 2. The spindle 36, 37 is connected to the slide 5 in a manner preventing axial movement relatively thereto, so that the slide 5 accompanies the spindle 36, 37 in any axial movement made by the latter relatively to the slide 3. The position of the stops 38 and 39 axially of the spindle 36, 37 can be adjusted by rotation of the latter, and the exact positioning of these stops and, hence, the amount of material to be removed during the ensuing grinding operation is determined by 20 a pointer 40 on the spindle 36, 37 cooperating with reference indicia on the slide 3 (Fig. 1a). The horizontal displacement of the slide 5 is effected by axial movement of the spindle 36, 37 relatively to the slide 3 by means of fluid pressure in a cylinder 41 mounted on the slide 3. The fluid pressure acts on a piston 42 connected to the spindle 36, 37. Movement of the piston 42 under fluid pressure thus displaces the spindle 36, 37 horizontally and, with it the slide 5 until, for example, the stop 39 contacts its abutment as shown in Fig. 2a. At this moment, a further rise of the fluid pressure acting on the piston 42 is prevented by the opening of two automatic excess pressure relief valves 43 provided in the piston 42. It is therefore in effect the hydraulic pressure that keeps the grinding wheel in operative contact with the work.

A dressing device 44 (Figs. 1a, 2a and 4) is mounted on the tool holder for reciprocation with respect thereto. It carries a cutting diamond which, with the device, is adapted to be displaced parallel to the working surface of the grinding wheel in order to effect a lateral truing or dressing of the latter. This is usually done between grinding operations, i. e. with the grinding wheel rim disengaged from the work. In order to be able to return the grinding wheel rapidly to its proper position in contact with the work on completion of a dressing operation, a manually operable knob 9 (Fig. 4) is provided which is secured to the axle pin of the ratchet wheel 18 and which can be turned to drive the gearing 19, 20 and the spindle 21 so as to effect the necessary horizontal movement of the tool-holder 12 towards the work. This is only a rough adjustment of the tool-holder to save time and the exact, fine setting of the tool holder and grinding wheel is then automatically carried out by means of the feeler device 16 in the manner already explained.

As the operative rim of the grinding wheel becomes unevenly worn in use it requires peripheral dressing (apart from the occasional lateral dressing by the device 44 above referred to), such peripheral dressing consisting in turning the grinding wheel down to a somewhat smaller diameter. For this purpose, a device in the form of a lever 33 (Figs. 1a and 4) is provided which car-

ries an appropriate cutting tool. After such a turning down operation, the grinding wheel, now of smaller diameter than before, must be raised again to its proper grinding position with its point of contact P disposed on the line of action of the gear teeth being ground. This is done by adjustment of the stops 29 already referred to so as to raise the slide 10, and with it the tool-holder 12 and the grinding wheel, relatively to the turn-table 6 by an amount corresponding to the reduction in diameter of the grinding wheel.

At the same time it is necessary for the turning-down device 33 and the feeler device 16 to be advanced towards the centre of the grinding wheel so as to remain in engagement with the operative rim thereof. This is arranged to take place automatically upon adjustment of the stops 29 by means of the spindle 32. For this purpose the spindle 32 is coupled to another screw-threaded spindle 34 by means of bevel gearing 35 (Figs. 1a and 2a). The devices 16 and 33 and associated parts are carried by a mounting which, as can also be seen from Fig. 4, has a bracket threadedly engaged by the spindle 34, so that 20 rotation of the latter causes sliding movement of the mounting along a part of the slide 10 to advance the devices 16 and 33 towards the grinding wheel 13.

In general the adjustment by means of the 30 stops 29 is used only to alter the vertical setting of the grinding wheel in accordance with its diameter, whereas the initial vertical adjustment of the grinding wheel to set its point of contact P on a given gear base circle or "line of action" 35 is effected by operation of the spindle 4 to raise or lower the slide 3, and with it the whole grinding wheel mounting apparatus, along the standard or frame 2. This would be the normal adjustment of the grinding wheel for work on gear 40 wheels of different diameters.

For the purpose of grinding internal gears with inclined (helical) teeth of involute form on this machine, the standard 2 is pivoted about the vertical axis C (pivot 55) which passes 45 through the point of intersection of the grinding wheel axis of rotation with the longitudinal central axis B of the machine. If the angle of inclination of the gear teeth (helix angle) is β , then the standard 2 is pivoted so that the plane 50 of the grinding wheel forms an angle β with the axis B of the machine, i. e. with the direction of forward movement of the work feed slide 48. The apparatus is shown in this position in Figs. 2 and 2a.

However, it is also necessary for the work to move on a helical path instead of the straight forward feed towards the grinding wheel imparted to it by the slide 48 parallel to the axis B of the machine. Such helical path of each 60 tooth flank being ground is of course necessary to ensure constant contact of the helical tooth flank with the grinding wheel. The gear being ground must therefore undergo an additional rotary motion of magnitude $dy = dx \cdot \tan \beta$ measured at the 65 base circle of the teeth being ground. For this purpose, the frame 52, to which the ends of the steel tapes 50 fastened to the rolling arc 49 are secured by means of the levers 51, is caused to be displaced transversely of the feed slide 48 on 70 which it is mounted for such relative movement, sliding thereover on rollers 53 (Fig. 3). This transverse movement of the frame 52 is caused to take place simultaneously with the movement whereby the slide 48 is fed forward towards the 75 grinding tool, and, it will be understood, that

thereby an additional rotation is imparted to the rolling arc 49 and to the gear wheel being ground, that is to say a rotation additional to that necessary for true rolling motion. In order to bring about this transverse movement of the frame 52, the latter has a pin 58 engaging in a guide groove or slot provided in a member 59 adjustably mounted on the machine bed 1. The member 59 is adapted to be angularly adjusted by means of a worm gear drive 60 (Fig. 2). If it is so adjusted that the guide slot forms an angle β with the longitudinal central axis B of the machine (this being the position shown in Fig. 2) then the frame 52 will be pulled laterally thereby as the feed slide 48 advances towards the grinding tool, the ratio of this lateral movement to the forward feed being $\tan \beta$. This lateral movement is of course transmitted by the steel tapes 50 to the rolling arc 49 and results in the correct additional rotary motion being imparted to the gear wheel being ground, so that the tooth flank in contact with the grinding wheel makes a helical movement with respect to the stationary working point of the latter. By adjusting the guide groove in the machine bed to $\beta=0^\circ$, that is to say parallel to the direction of movement of the feed slide 48 (i. e. to the longitudinal central plane B of the machine), there is no lateral displacement of the frame 52, and the machine is ready for grinding the straight teeth of ordinary internally toothed spur gear wheels.

The method of obtaining motive power for the movement of the parts described in the foregoing has not been thought worthy of special mention, as many such methods are well known and understood in the art, any of which can be applied to the machine above described.

While a preferred embodiment of this invention has been described in the foregoing, it will be appreciated by those skilled in the art that many modifications may be made in the details of construction, disposition and cooperative arrangements of the parts without departing from the spirit of the invention which, therefore, is not to be deemed to be limited by the foregoing description or otherwise than by the scope of the appended claims.

What I claim and desire to secure by Letters Patent is:

1. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure on which said tool-holder is mounted for pivotal movement about a pivotal axis disposed perpendicularly to, but not intersecting, the axis of rotation of said grinding wheel, and means for effecting said pivotal movement of said tool-holder to locate said grinding wheel in positions approximately 180° apart with respect to said pivotal axis for grinding one flank of the teeth of the work in one of said positions and the other flank in the other of said positions.

2. Machine for grinding the tooth flanks of internally toothed gear wheels comprising a single grinding wheel having a narrow active rim adjacent the periphery thereof for making sub-

stantially point contact with the work, the working point of said rim being in operation disposed on the "line of action" of the teeth of the work, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure on which said tool-holder is mounted for pivotal movement about a pivotal axis disposed perpendicularly to, but not intersecting, the axis of rotation of said grinding wheel and for linear sliding movement in a plane perpendicular to said pivotal axis, adjustable stop means for limiting said sliding movement of said tool-holder in both directions, said grinding wheel having one position, determined by said stop means, for grinding one flank of the teeth of the work, means for effecting said pivotal movement of said tool-holder through approximately 180° to invert said grinding wheel from said position thereof and locate its working point beyond the "line of action," and means for automatically effecting said sliding movement of said tool-holder to move said grinding wheel linearly to another position, also determined by said stop means, in which its working point is again located on the "line of action," for grinding the other flank of the teeth of the work.

3. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure on which said tool-holder is mounted for pivotal movement about a substantially horizontal pivotal axis disposed above, and perpendicular to, the axis of rotation of said grinding wheel, and for linear sliding movement in a plane perpendicular to said pivotal axis, adjustable stop means for limiting said sliding movement of said tool-holder in both directions, said grinding wheel being adapted in one position thereof to grind one flank of the teeth of the work, means for effecting said pivotal movement of said tool-holder through approximately 180° to invert said grinding wheel from said position thereof and locate said axis of rotation thereof above said pivotal axis, and means for automatically effecting said sliding movement of said tool-holder to lower said grinding wheel inverted to another position thereof and restore said axis of rotation thereof to the same level below said pivotal axis as before said pivotal movement, said grinding wheel being adapted, in said other position thereof, to grind the other flank of the teeth.

4. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure including a supporting member, a turn-table member mounted

for rotation on said supporting member about a substantially horizontal pivotal axis disposed above, and perpendicularly to, the axis of rotation of said grinding wheel, a slide member mounted on said turn-table member for free gravitational linear sliding movement relatively thereto in a plane perpendicular to said pivotal axis, two adjustable stop means alternately effective for limiting said sliding movement of said slide member in either direction depending on the position to which said turn-table member has been rotated, said tool-holder being carried by said slide member which, in one position thereof determined by one of said stop means, locates said grinding wheel for grinding one flank of the teeth of the work, and means for rotating said turn-table member about said pivotal axis through approximately 180° to invert said slide member and cause it to be lowered by gravity to another position thereof determined by the other of said stop means, said slide member, when inverted in said other position thereof, locating said grinding wheel for grinding the other flank of the teeth of the work.

5. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure including a supporting member, a turn-table member mounted for rotation on said supporting member about a substantially horizontal pivotal axis disposed above, and perpendicularly to, the axis of rotation of said grinding wheel, a slide member mounted on said turn-table member for free gravitational linear sliding movement relatively thereto in a plane perpendicular to said pivotal axis, two adjustable stop means alternately effective for limiting said sliding movement of said slide member in either direction depending on the position to which said turn-table member has been rotated, said tool-holder being mounted on said slide member for substantially horizontal sliding adjustment with respect thereto in the direction of said grinding wheel axis of rotation, said slide member, when in one position thereof determined by one of said stop means, locating said grinding wheel for grinding one flank of the teeth of the work, means for rotating said turn-table member about said pivotal axis through approximately 180° to invert said slide member and cause it to be lowered by gravity to another position thereof determined by the other of said stop means, said slide member, when inverted in said other position thereof, locating said grinding wheel for grinding the other flank of the teeth of the work, a cutting device adjustably mounted on said tool-holder supporting structure for dressing the periphery of said grinding wheel by reducing the diameter thereof, a feeler device adjustably mounted on said tool-holder supporting structure for sensing the position of said grinding wheel axially thereof relatively to the work and correspondingly causing said tool-holder to be automatically adjusted horizontally with respect to said slide member to move said grinding wheel axially thereof towards the work in compensation for wear of said grinding wheel, and means common to said stop means, said cutting device and

said feeler device for adjusting both said stop means to determine said positions of said slide member in accordance with the diameter of said grinding wheel and for simultaneously adjusting the position of said cutting device and said feeler device to remain in engagement with said grinding wheel upon reduction of the diameter thereof.

6. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure including a supporting member, a turn-table member mounted for rotation on said supporting member about a substantially horizontal pivotal axis disposed above, and perpendicularly to, the axis of rotation of said grinding wheel, a slide member mounted on said turn-table member for free gravitational linear sliding movement relatively thereto in a plane perpendicular to said pivotal axis, two adjustable stop means alternately effective for limiting said sliding movement of said slide member in either direction depending on the position to which said turn-table member has been rotated, 20 said tool-holder being mounted on said slide member for substantially horizontal sliding adjustment with respect thereto in the direction of said grinding wheel axis of rotation, said slide member when in one position thereof determined by one of said stop means, locating said grinding wheel for grinding one flank of the teeth of the work, means for rotating said turn-table member about said pivotal axis through approximately 180° to invert said slide member and cause it to be lowered by gravity to another position thereof determined by the other of said stop means, said slide member, when inverted in said other position thereof, locating said grinding wheel for grinding the other flank of the teeth of the work, 30 a device for dressing the periphery of said grinding wheel by reducing the diameter thereof, a device for dressing the side of said grinding wheel and a feeler device for sensing the position of said grinding wheel axially thereof relatively to the work and correspondingly causing said tool-holder to be automatically adjusted horizontally with respect to said slide member to move said grinding wheel axially thereof towards the work in compensation for wear of said grinding wheel, said dressing devices and said feeler device being mounted on said tool-holding supporting structure for rotation with said turn-table member about said pivotal axis.

7. Machine for grinding the tooth flanks of internally toothed gear wheels comprising a single grinding wheel, a tool-holder on which said grinding wheel is mounted for rotation, driving means for rotating said grinding wheel, a work-holder, driving means for imparting to said work-holder a feed motion towards said grinding wheel and simultaneously an involute generating rolling motion with respect to said grinding wheel, a tool-holder supporting structure including a supporting member, a first slide member mounted on said supporting member for substantially horizontal sliding adjustment with respect thereto in the direction of the axis of rotation of said grinding wheel, a turn-table member mounted for rotation on said first slide member about a substantially horizontal pivotal axis disposed above,

75

and perpendicular to, said grinding wheel axis of rotation, a second slide member mounted on said turn-table member for free gravitational linear sliding movement relatively thereto in a plane perpendicular to said pivotal axis, two adjustable stop means alternately effective for limiting said sliding movement of said second slide member in either direction depending on the position to which said turn-table member has been rotated, said tool-holder being carried by said second slide member which, in one position thereof determined by one of said stop means, locates said grinding wheel for grinding one flank of the teeth of the work, means for rotating said turn-table member about said pivotal axis through approximately 180° to invert said second slide member and cause it to be lowered by gravity to another position thereof determined by the other of said stop means, said second slide member, when inverted in said other position thereof, locating said grinding wheel for grinding the other flank of the teeth of the work, and operating means for causing said sliding adjustment of said first slide member to move said grinding wheel axially thereof away from the work prior to said rotation of said turn-table member and towards the work after said rotation of said turn-table member and to determine the depth of material to be removed from the work by said grinding wheel.

8. Machine for grinding the tooth flanks of internally toothed gear wheels comprising a machine bed and work-supporting and tool-supporting structures mounted on said bed, said work-supporting structure including a feed slide mounted on said bed for movement longitudinally thereof towards said tool-supporting structure, a traversing slide mounted on said feed slide for reciprocating movement relatively thereto perpendicularly to the direction of movement of said feed slide, driving means for causing said movements of said feed slide and said traversing slide, a frame mounted on said feed slide, a rolling arc rotatably mounted on said traversing slide upon an axis parallel to the direction of movement of said feed slide, flexible steel tapes stretched between, and secured to, said frame and the circumference of said rolling arc so as to cause rotation of the latter as it reciprocates with said traversing slide relatively to said frame, a work-holder mounted on said traversing slide coaxially with, and coupled to, said rolling arc to move the work with true involute generating rolling motion to and fro past said tool-supporting structure, and said tool-supporting structure including a single grinding wheel having a narrow active rim adjacent the periphery thereof for making substantially point contact with the work, the working point of said rim being in operation disposed on the "line of action" of the teeth of the work, a tool-holder on which said grinding wheel is mounted for rotation, driving means for rotating said grinding wheel, a supporting member carried by said bed and having said tool-holder mounted thereon for pivotal movement about a substantially horizontal pivotal axis disposed perpendicularly to, but not intersecting, the axis of rotation of said grinding wheel and for linear sliding movement in a plane perpendicular to said pivotal axis, adjustable stop means for limiting said sliding movement of said tool-holder in both directions, said grinding wheel having one position, determined by said stop means, for grinding one flank of the teeth of the work, means for effecting said pivotal movement of said tool-holder through approximately 180° to invert said

grinding wheel from said position thereof and locate its working point beyond the "line of action," and means for automatically effecting said sliding movement of said tool-holder to move said grinding wheel linearly to another position, also determined by said stop means, in which its working point is again located on the "line of action," for grinding the other flank of the teeth of the work.

9. Machine for grinding the tooth flanks of internally toothed helical gear wheels comprising a machine bed and work-supporting and tool-supporting structures mounted on said bed, said work-supporting structure including a feed slide mounted on said bed for movement longitudinally thereof towards said tool-supporting structure, a traversing slide mounted on said feed slide for reciprocating movement relatively thereto perpendicularly to the direction of movement of said feed slide, driving means for causing said movements of said feed slide and said traversing slide, a frame mounted on said feed slide for movement relatively thereto perpendicularly to the direction of movement thereof, a member adjustably secured to said bed and having a guide slot therein, means for adjusting said member so that said guide slot forms an angle with the direction of movement of said feed slide equal to the helix angle of the teeth of the work, a guide member on said frame engaging said guide slot to cause said frame to make said movement relatively to said feed slide as the latter moves forward towards said tool-supporting structure, a rolling arc rotatably mounted on said traversing slide upon an axis parallel to the direction of movement of said feed slide, flexible steel tapes stretched between, and secured to, said frame and the circumference of said rolling arc so as to cause rotation of the latter as it reciprocates with said traversing slide relatively to said frame, the combined movement of said rolling arc being true rolling motion plus an additional rotary motion which is a function of the helix angle of the teeth of the work, a work-holder mounted on said traversing slide coaxially with, and coupled to, said rolling arc to move the work to and fro past said tool-supporting structure with the correct motion for generating involute helical gear teeth, and said tool-supporting structure including a single grinding wheel having a narrow active rim adjacent the periphery thereof for making substantially point contact with the work, the working point of said rim being in operation disposed on the "line of action" of the teeth of the work, 30 a tool-holder on which said grinding wheel is mounted for rotation, driving means for rotating said grinding wheel, a supporting member carrying said tool-holder and being mounted on said bed for swivelling movement about a vertical axis to set the general plane of said grinding wheel at an angle to the direction of movement of said feed slide equal to the helix angle of the teeth of the work, said tool-holder being mounted on said supporting member for pivotal movement about 35 a substantially horizontal pivotal axis disposed perpendicularly to, but not intersecting, the axis of rotation of said grinding wheel and for linear sliding movement in a plane perpendicular to said pivotal axis, adjustable stop means for limiting said sliding movement of said tool-holder in both directions, said grinding wheel having one position determined by said stop means for grinding one flank of the teeth of the work, means for effecting said pivotal movement of said tool-holder through approximately 180° to invert said grind-

ing wheel from said position thereof and locate its working point beyond the "line of action," and means for automatically effecting said sliding movement of said tool-holder to move said grinding wheel linearly to another position, also determined by said stop means, in which its working point is again located on the "line of action," for grinding the other flank of the teeth of the work.
